UNITED STATES PATENT OFFICE.

JOHN OSBOURNE WOODSOME, OF NEW YORK, N. Y.

STEAM-CIRCULATING FITTING.

Application filed January 16, 1925. Serial No. 2,868.

In paper making machines, the drying cylinders are supplied with heating steam at low pressure from any desired source since the pressure of heating steam commonly used does not have to be very great. The heating steam has to be admitted into the interior of the drying cylinders and the water of condensation must be extracted from the heating cylinders.

This invention relates to an improved Venturi type circulating fitting and a condensate remover for use in connection with paper making machine drying cylinders whereby a satisfactory removal of air, non-condensable gases and condensed steam from the drying cylinders is accomplished by means of a suction or vacuum produced in the improved circulating fitting which is connected to admit heating steam into the drying cylinders.

It is an object of this invention to provide an improved steam circulating fitting of simplified construction adapted to be connected in the piping system of a paper making machine drying cylinder for the purpose of efficiently drawing off the water of condensation, air and non-condensable gases, thereby increasing the working capacity of the drying cylinder.

It is also an object of this invention to provide means within the steam supply leads of the paper making machine drying cylinders adapted to cause a suction in the cylinder exhaust pipes whereby the condensate may be withdrawn from the drying cylinder and returned to the main steam supply pipe.

It is a further object of this invention to provide a steam circulating fitting adapted to be connected in the steam inlet pipe of a paper making machine drying cylinder, said fitting being constructed with a restricted steam passage which communicates with a larger expansion passage to create a suction in the fitting whereby the condensate, air and gases, are withdrawn from the drying cylinders through outlet pipes connected with the fitting at the point of the restricted passage.

It is an important object of this invention to provide an improved fitting of simple and improved construction without moving parts and adapted to be used in steam circulating systems to create a suction whereby steam, water, air and gas may be withdrawn through an exhaust outlet pipe connected with the improved fitting.

Other and further important objects of this invention will be apparent from the disclosures in the specification and the accompanying drawings.

This invention (in a preferred form) is illustrated in the drawings and hereinafter more fully described.

On the drawings:

Figure 1 illustrates a fragmentary side elevation of a paper making machine drying unit wherein the drying cylinders have improved steam circulating fittings embodying the principles of this invention connected in the steam inlet pipes.

Figure 2 is an enlarged elevation of the improved steam circulating fitting.

Figure 3 is a longitudinal section thereof taken on line III—III of Figure 2.

Figure 4 is an enlarged transverse section taken on line IV—IV of Figure 3.

As shown on the drawings:

The reference numeral 1 indicates the frame of a drying unit of a paper making machine, said frame having mounted thereon in any desired manner, a plurality of paper drying cylinders 2, each of which is provided at one end with a trunnion 3 constructed to afford both an admission opening for the heating steam and an opening to take care of the exhaust of the condensed steam.

While a plurality of drying cylinders have been illustrated in Figure 1, the piping system for only one of said cylinders will be described in detail. The arrangement of the piping is the same for all of the drying cylinders and is believed to be clearly illustrated in Figure 1. Connected in the steam inlet opening of the trunnion 3, is a steam inlet pipe 4, the lower end of which is connected to a globe valve 5. Threaded into the globe valve 5 is a threaded sleeve 6 forming a part of the improved steam circulating fitting of this invention. The fitting comprises a collar 7 in one end of which the flanged end of the sleeve 6 is engaged; also connected in the collar 7 is the enlarged end of a conical section embracing a plurality of frustum shaped sleeves 8, 9, 10 and 11, the interiors of which communicate to afford a continuous conical chamber 12, the enlarged end of which leads into the sleeve 6.

The sleeve 11 is externally flanged at 13 and externally threaded below said flange at 14. The sleeve 11 is provided with a steam inlet opening at 15. Threaded onto the threaded portion 14 of the sleeve 11 is a Venturi cast

ing comprising a cylindrical portion 16 and a conical portion 17 the outer end of which is provided with an internally threaded flange 18. The conical portion 17 has a tapered chamber 19, the small end of which is restricted at 20. The restricted opening 20 communicates with the opening 15 in the reduced end of the sleeve 11. Also integrally formed on the side of the Venturi casting 10 is an internally threaded arm 21. A passage 22 is provided in the Venturi casting and connects the openings 15 and 20 with the interior of the arm 21 (Figure 3). Threaded into the flange 18 is a frustum shaped sleeve 23 the interior of which is provided with a tapered chamber communicating with the chamber 19 in the casting portion 17. Externally threaded on the enlarged arm 23 is a collar 24 having the flanged end of a 15 sleeve 25 engaged therein.

Connected to the sleeve 25 is a steam pipe 26 the lower end of which is connected at one end of an elbow 27. Threaded into the other end of the elbow 27 is one end of a connecting pipe 28 the other end of which is engaged in one arm of a four way connector or cross 29. A connecting pipe 30 is also connected with the cross 29 and has one end thereof attached to receive steam from a steam 30 supply main or pipe 31. Projecting through the cross 29 is a drain pipe 32 the upper end of which is connected with a tee 33. The pipe 32 also projects through the pipe 30 and enters the main pipe 31. A pipe 34 is 35 connected with one arm of the tee 33 and is provided with a check valve 35. The pipe 34 is connected to the lower arm of a condensate trap 36 which communicates with the arm 21 of the Venturi casting by means of a pipe 37. Also connected with the trap 36 at one end is an exhaust or outlet pipe 38 having a globe valve 39 therein. The exhaust pipe 38 is also connected in the condensate outlet opening provided in the 40 trunnion 3 of the drying cylinder.

The operation is as follows:

In paper making machines a wet web of paper to be dried is conducted between a plurality of the drying cylinders 2 which are 50 rotated by any suitable means and are sometimes heated by steam. Steam is admitted through the steam supply pipe 31 and passes upwardly through the pipe 30 and the cross 29 and the pipe 28 through the elbow 27 and 55 the pipe 26 through the lower sleeve 25 of the Venturi type circulating fitting of this invention. From the sleeve 25 the steam passes through the tapered chamber of the sleeve 23 and to the chamber 19 and then 60 continues through the restricted opening 20 upwardly through the opening 15 into the long tapered chamber 12 provided in the series of connecting sleeves 8 to 11 inclusive. The entering steam is thus compressed as 65 it passes through the restricted Venturi

opening 20 and is permitted to expand as it reaches the enlarged opening 15 and the passage 12. This compression and expansion of the steam acts to produce a substantial vacuum in the Venturi type circulating fitting thereby causing a suction through the passage 22 leading through the arm 21 and the trap 36. A suction is thus also produced in the exhaust pipe 38 leading from the cylinder trunnion 3 so that the water of condensation from the cylinder 2 resulting from the drying of the paper web is drawn out of the cylinder together with a small quantity of steam which may be mixed with the water of condensation. The water of condensation together with any steam mixed therewith is thus readily removed from the cylinder and passes into the trap 36 which is constructed to cause the entrapped steam to be drawn through the passage 22 into the Venturi circulating fitting due to the suction produced therein. The water of condensation, however, passes from the trap 36 downwardly through the pipe 34 and the check valve 35, then through the tee 33 and the pipe 32 which extends through the cross 29 and the pipe 30 to permit the water of condensation to flow back into the steam supply pipe 31.

The same operation takes place in each of the drying cylinders of the paper making machine drying unit, and affords means for efficiently removing the water of condensation from the drying cylinders due to the creation of a suction or vacuum in the Venturi type circulating fittings connected in the steam inlet pipes leading to the trunnions of the steam caps provided on the various drying cylinders.

I am aware that many changes may be made and numerous details of construction may be varied through a wide range without departing from the principles of this invention, and I therefore do not purpose limiting the patent granted hereon, otherwise than necessitated by the prior art.

I claim as my invention:

1. The combination with a paper making machine drying cylinder, of a steam supply pipe, a steam inlet pipe connecting the steam supply pipe with the interior of the said drying cylinder, and a Venturi type steam circulating fitting connected in said steam inlet pipe.

2. The combination with a paper making machine drying cylinder, of a steam supply pipe, a steam inlet pipe connecting the steam supply pipe with the trunnion of said cylinder, a Venturi type circulating fitting connected in said steam inlet pipe to produce a suction or vacuum therein, and a condensate exhaust pipe connected with the cylinder trunnion, with the fitting and with said steam supply pipe.

3. The combination with a paper making

machine drying cylinder, and the steam intake trunnion thereof, of a steam supply pipe, a steam inlet pipe connecting said steam supply pipe with the cylinder trunnion, a Venturi type circulating fitting connected in said inlet pipe and constructed to produce a substantial suction or vacuum therein, a trap connected with said fitting, a condensate exhaust pipe connected with the cylinder trunnion and with the said trap, and piping connections connecting said trap with said steam supply pipe.

4. The combination with a paper making machine drying cylinder, and the steam intake trunnion thereof, of a steam supply pipe, a steam inlet pipe connecting the steam supply pipe with the cylinder trunnion, a Venturi type circulating fitting connected in said steam inlet pipe and having a restricted passage therein to cause the creation of a substantial suction or vacuum in an arm of said fitting, a trap connected with said arm, an exhaust pipe connecting said trap with the cylinder trunnion whereby the water of condensation, air, and non-condensable gases in the cylinder are drawn therefrom into the trap due to the action of said suction or vacuum, and piping connections leading from the trap back to the steam supply pipe to permit the water of condensation to be returned to the steam supply pipe while any steam entering said trap is drawn back into the fitting.

5. The combination with a paper making machine drying cylinder and the steam supply pipe therefor, of a condensate return pipe and a steam supply inlet pipe connecting said cylinder with the steam supply pipe, a trap connected in said condensate return pipe, and means connected in the steam inlet pipe communicating with said trap adapted to produce suction or a vacuum sufficient to draw the water of condensation from the cylinder into the trap for return to the steam supply pipe.

6. The combination with a steam heated cylinder, of a steam supply pipe, a condensate exhaust pipe connecting said cylinder with said steam supply pipe, and a suction or vacuum producing means in said steam supply pipe and connected with the condensate exhaust pipe to cause the water of con-

densate from said cylinder to be drawn through the condensate exhaust pipe and returned to the steam supply pipe.

7. The combination with a steam heated drying cylinder and a trunnion thereof, of a steam inlet pipe and a condensate exhaust pipe connected with said trunnion, and a Venturi type circulating fitting connecting said steam inlet pipe and said condensate exhaust pipe adapted to create a substantial suction or vacuum to draw the water of condensation from said cylinder.

8. The combination with a steam heated cylinder and a trunnion thereof, of a steam inlet pipe connected with said trunnion, and a suction and a vacuum producing fitting connected in said steam inlet pipe and comprising a plurality of connected sleeves constructed to afford a restricted passage for steam therein.

9. The combination with a steam heated cylinder and a trunnion thereof, of a steam inlet pipe, of a fitting connected therein comprising a casting having an arm integrally formed thereon, said casting having a restricted opening therein, and a passage connecting said opening with the interior of said arm, sleeves connected with both ends of said casting to afford converging conical passages leading from said casting to afford a means of producing a substantial suction or vacuum in said arm when steam passes through the restricted opening, and through the converging passages.

10. The combination with a steam heated dryer and steam supply pipe therefor, of means for removing condensed steam, entrapped air and non-condensable gases from said dryer comprising a steam inlet pipe connecting said supply pipe and dryer, a Venturi type fitting connected in said inlet pipe, a condensate exhaust pipe leading from said dryer and connected to the constricted portion of said fitting whereby suction is created in said exhaust pipe and a separator in said exhaust pipe whereby the air and non-condensable gases free from condensate are allowed to be drawn back into said fitting.

In testimony whereof I have hereunto subscribed my name.

JOHN OSBOURNE WOODSOME.
